(57) **CLAIM**

The ornamental design for a toy gun, as shown and described.

DESCRIPTION

FIG. 1 is a front perspective view of a toy gun, showing my new design;

FIG. 2 is a rear perspective view thereof;

FIG. 3 is an enlarged plan view of the front;

FIG. 4 is an enlarged plan view of the rear;

FIG. 5 is an enlarged plan view of the left side;

FIG. 6 is an enlarged plan view of the right side;

FIG. 7 is an enlarged plan view of its top surface; and,

FIG. 8 is an enlarged plan view of its bottom surface.

The broken lines in the drawings illustrate the portions of the toy gun, which form no part of the claimed design.
